Primary Examiner — Jeffrey D Asch(74) *Attorney, Agent, or Firm* — Hamilton & Terrile, LLP;
Robert W. Holland(57) **CLAIM**

The ornamental design for a mobile telephone handset, as shown and described.

DESCRIPTION

FIG. 1 is a front perspective view of the mobile telephone handset comprising the present invention;

FIG. 2 is a front view thereof;

FIG. 3 is a right side view thereof;

FIG. 4 is a left side view thereof;

FIG. 5 is a back view thereof;

FIG. 6 is a top view thereof; and,

FIG. 7 is a bottom view thereof.

The broken lines shown throughout the views that are immediately adjacent to the shaded areas, and define unshaded regions, represent the bounds of the claimed design, while all other broken lines are directed to environment and are for illustrative purposes only; the broken lines form no part of the claimed design.
